CLAIM

The ornamental design for a storage drive, as shown and described.

DESCRIPTION

FIG. 1 is a top, front and side perspective view of a storage drive embodying the new design.

FIG. 2 is a top view thereof.

FIG. 3 is a detail view of the top view taken along line 3-3 of FIG. 2.

FIG. 4 is a bottom view thereof.

FIG. 5 is a back view thereof.

FIG. 6 is a front view thereof.

FIG. 7 is a first side view thereof; and,

FIG. 8 is a second side view thereof.

Broken lines are used to illustrate features of the storage drive which form no part of the claimed design. The broken line 3-3 in FIG. 2 forms no part of the claimed design.

1 Claim, 5 Drawing Sheets
